(57) **CLAIM**

The ornamental design for a meat trimmer, as shown and described.

DESCRIPTION

FIG. 1 is a front-left side perspective view of a meat trimmer showing my new design;

FIG. 2 is a bottom-right side perspective view thereof;

FIG. 3 is a rear-left side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a bottom plan view thereof;

FIG. 9 is a top plan view thereof;

FIG. 10 is a front elevational view thereof, showing the plane upon which a cross-sectional view is taken and shown in FIG. 11; and,

FIG. 11 is a cross-section view thereof taken along line 11-11 of FIG. 10.
